UNITED STATES PATENT OFFICE.

ALBERT F. SCHROEDER, OF CLEVELAND, OHIO.

REEL.

1,243,450.

Specification of Letters Patent. Patented Oct. 16, 1917.

Application filed February 4, 1915. Serial No. 6,060.

To all whom it may concern:

Be it known that I, ALBERT F. SCHROEDER, a citizen of the United States, residing at Cleveland, in the county of Cuyahoga and State of Ohio, have invented a new and useful Improvement in Reels, of which the following is a specification, the principle of the invention being herein explained and the best mode in which I have contemplated applying that principle, so as to distinguish it from other inventions.

My invention has general reference to reels and more particularly to articles of this character involving a journal and a rather large hub and heads.

One object of this invention is to improve the structure of reels in respect to certain details of manufacture, and as an incidental advantage the mode of assemblage. Other objects are to provide a reel which will be durable, slight in appearance and economical to produce. Especial objects are:

1. To provide a reel presenting a smooth and absolutely close mechanical fit between the hub and heads.

2. To provide a reel involving a reduction in the number of breaks heretofore required in the exterior surfaces of the heads.

The inventive conception is associated with elements which are hereinafter explained and variously combined in the claims. While the annexed drawing and particular description thereof set forth the preferred form embodying my invention, it should be understood that the means merely exemplifies one of many diversified mechanical forms with which the principle of my invention may be properly applied.

Adverting to the drawings:

Figure I is a plan or elevation of a reel embodying my invention.

Fig. II is mainly a section of Fig. I certain parts being in elevation.

Fig. III is an end elevation of Fig. I looking in direction indicated by the arrows in Fig. II.

Fig. IV is a view corresponding to Fig. II of a simplified modification.

The structure of a reel embodying my invention comprises a pair of circular heads 1 having concave peripheral flanges 2 adapted to serve as pulleys. Each of the heads, which are of identical form and structure throughout, is provided with a central opening 3, and also with a plurality, and in this exemplification with three, circularly ar-

ranged outwardly-offset apertures 4. Carried upon the inside or opposed surfaces of the heads 1 as by spot-welding are a pair of cupped plates 5. These plates are similarly provided each with a central opening 6 which is of the same bore and registers with one of the central openings 3. As will be observed upon inspection of Fig. II the plates 5 are likewise similarly provided with three circularly arranged apertures 7 each registering with one of the apertures 4. The plates 5 are flat except for the annular inwardly projected peripheral flanges 8.

A shaft 9 having reduced ends 10 which are accurately fitted to the openings 3 and 6, includes in its contour a pair of right angled shoulders 11 intended to abut the inner sides of the plates 5. A hollow cylindrical drum 12 corresponding precisely in length with the distance between the shoulders 11, and of inside diameter precisely with the exterior diameter of the flanges 8, is shown to be positioned between the heads 1 so as to snugly inclose such flanges. In this manner the drum 12 may be readily centered due to the concentricity of the flanges 8. Another feature, however, of my arrangement is that a smooth tightly abutting corner fit between the heads 1 and the drum is effected, whereby no crevice appears. This is an important advantage which is offered by my construction because when a reel has loose fibers wound about its drum it is desirable not to have any such catch or wedge in the outer corners to become disrupted or disarranged or to hinder a smooth continuation in the winding operation. The drum 12 is in Fig. I seen to be fashioned with a slot 13 intended to secure the end of the material which is to be wound upon it.

A pair of collars 14 are positioned as a shrunk fit upon the outwardly projecting ends 10 so as to tightly abut the outer sides of the heads 1 thereby very firmly binding the same together with the plates 5 against the shoulders 11. In this manner the essential parts of the reel are well secured at the center and at the same time the shaft 9 is reinforced adjacent to its journal.

As an auxiliary fastening means three rods 15 having heads 16 are passed through the apertures 4 and 7 to be riveted over at 17. It is obvious that with the use of a spinning riveting machine a very neat and effective securing means may be thus accom-

plished just inwardly, and at three equidistant points, of the periphery of the drum 12. The smooth slightly appearance which the ends or outer sides of the heads of my reel 5 structure presents should commend itself further as a commercial asset.

The modification shown in Fig. IV resides in a simplification of the centering and reinforcing plates 18. These will be seen to be 10 provided in the same way as before with central openings 19 and circularly arranged apertures 20 but with the peripheral flanges omitted. For certain purposes the normal edges of the plates 18 would offer a sufficient 15 bearing and centering surface and incidentally permit the use of material, otherwise to become scrap stock, which might not be of suitable size to permit the formation of peripheral flanges.

20 In being thus enabled to utilize scrap 5 punchings to serve the purposes of either the plates 5 and 18, my invention involves a pronounced manufacturing expedient of which a new and useful result is predicated.

25 I claim:—

1. A reel comprising a pair of circular heads each having a central opening and a plurality of circularly arranged apertures having offset edges, a pair of disks each 30 having an opening and apertures correspondingly arranged as and registering inwardly with said head openings and apertures respectively, a drum interposed between said heads and inclosing said disks, 35 a series of rods joining said heads to-

gether and having ends flanged over said offset edges, a shaft having reduced ends passing through said central openings whereby the reel may be rotatably mounted, said shaft having a shoulder abutting the inside of said heads and collars for fixing 40 said heads against such shoulders.

2. A reel comprising a pair of circular heads each having a central opening and a plurality of circumferentially arranged apertures, a pair of disks each having a central opening and circumferentially arranged apertures adapted to register inwardly adjacent to said head openings and apertures respectively, a cylindrical drum interposed 50 between said heads and snugly inclosing said disks so as to be concentrically supported, a series of rods passed through aligned pairs of said registering apertures for joining said heads together, a shaft extending through the four central openings and having reduced ends whereby to form shoulders abutting the inside surfaces of said disks, and collars shrunk upon the ends of said shaft and tightly abutting the outside 60 surfaces of said heads whereby to firmly clamp said heads and disks together against said shoulders.

Signed by me this 2nd day of February, 1915.

ALBERT F. SCHROEDER.
